189,740

EMBROIDERED WEBBING OR THE LIKE

Martin M. Nelson, 165 Schenk Circle, Hewlett, N.Y.

Filed Aug. 5, 1960, Ser. No. 61,633

Term of patent 7 years

(Cl. D3—9)

The figure is a plan view of an embroidered webbing or the like, showing my new design.

I claim:

The ornamental design for an embroidered webbing or the like, substantially as shown.

References Cited in the file of this patent

UNITED STATES PATENTS

D. 35,961	Landenberger	-----	June 17, 1902
D. 92,434	Stern	-----	June 5, 1934
D. 183,476	Beer	-----	Sept. 9, 1958